METHOD AND APPARATUS FOR THE CONTINUOUS PRODUCTION OF CARBON DISULPHIDE

Ernest Charles, Clamecy, France, assignor to Societe des Produits Chimiques de Clamecy, Clamecy, France, a corporation of France

Application June 10, 1949, Serial No. 98,346

Claims priority, application France June 12, 1948

2 Claims. (Cl. 23—277)

1

This invention relates to a method and to means for reacting coal and sulfur for the formation of carbon disulfide.

It is an object of the invention to organize the formation of the carbon disulfide in such manner as to reduce to a minimum the amount of heat energy to be introduced from the outside into the zone of reaction.

The new method is characterized essentially by the introduction, into the reaction zone, of the coal freed from volatile gases and the sulfur after both have been preheated to the reaction temperature. The losses of heat in this zone are prevented by heat insulating or slightly heating the reaction vessel, the heat produced in the reaction being utilized under the best possible conditions for preheating the sulphur and the coal and obtaining the inexpensive purification of the carbon disulphide.

It is known that the reaction between sulfur and coal (which is endothermic at ordinary temperature) is exothermic at the reaction temperature, ranging from about 900° and 1,000° C. Thus in the production of carbon disulphide the heat energy to be provided from the outside is consumed in the preheating of the sulfur and the coal.

When operating batchwise with heat energy supplied from the outside unsatisfactory results are obtained because the transmission of heat through the charcoal layer is poor. Electric heat energy for raising the temperature of the sulphur and the coal is expensive. The main objection to the introduction of charcoal at a low temperature into the oven is that this product has a high gas content so that a large amount of sulphur will be lost in the non-condensable gases.

Therefore according to the present invention the gases are removed from the charcoal when heating it and then exhausted from the reaction oven.

The equipment whereby the new process may be carried into effect comprises essentially: a vertical reaction retort having little or no loss of heat, a vertical coal preheating retort, placed on top of the reaction retort and heated by means of injected air and gas, a superheater adapted to heat the sulphur vapor to the reaction temperature, and means for melting and vaporizing the sulphur treated and for rectifying the carbon disulphide.

In the drawing affixed to this specification and forming part thereof the invention is illustrated diagrammatically by way of example.

Referring to the drawing coal (in any form, natural or agglomerated, with or without sul-

phur catalysts or substances adapted to change the melting temperature of the ashes) is fed into the hopper 1. It is then discharged into the heat-insulated coal preheating retort 10 through the medium of a gas-tight distributor 2. During its downward travel the coal is heated by passing in front of the blast-pipe 9 fed with air under pressure from a suitable source (not shown) through a conduit 8 and with gases fed from the distillation of the charcoal through a conduit 7. The red-hot charcoal descends into the upper portion of the retort 13 which is kept under constant pressure by means of the automatic regulator 33 having its pressure-intake at 34. The coal distillation gases are taken up at 3 by the fan 4 and forced through the blast-pipe 9 into a hearth of the sulfur superheater 18. In order to prevent the vapor from penetrating into the coal pre-heating retort 10 a very low pressure is maintained in the bottom portion of this retort, and this very low pressure is transmitted through the pressure intake 11 to the automatic regulator 5. Due to the considerable loss of charge occurring between the two ends of the pre-heating oven 10 the amount of inert gas penetrating into the reaction retort 13 is insignificant.

The solid sulphur introduced into the hopper 26 is fed by the screw conveyor 27 into the melting tunnel 24 provided with an agitator 23. This tunnel is heated by means of a cluster of tubular elements.

The molten sulphur passes through the filter 28 and is then fed to the bottom portion of the vaporizer 21. The sulphur vapor is then superheated in the superheater 19 positioned in the compartment 20 of the apparatus and is introduced at 12 into the top portion of the reaction retort 13. The fore-hearth 18 is partially fed at 15 with the gases from the distillation of the coal in the pre-heating retort 10, the complementary heat-units being fed through a conduit 6 from any suitable source on the outside. In addition air is injected at 17.

The combustion gases during their travel meet the sulphur at 24 and melt it and the molten sulphur is vaporized in heater 21. It is therefore apparent that the hot gases and the sulphur vapor travel in a counter-current. The burnt gases and sulphur also travel in counter-current. The burnt gases escaping through the flue 25 and a stack (not shown).

The superheated sulfur vapor and the pre-heated coal react inside the reaction retort 13. The vapor of crude carbon disulphide (containing sulphur and non-condensable gases) passes through the shutters 41 to a heat exchange coil

37 in a column 36 where the crude carbon disulfide and intermixed gases are reduced in temperature after which such gases pass to the sulphur separating column 40. Liquid sulphur is sprinkled into the top portion of the column 40 from a source presently to be explained in order to bring about a separation of the sulphur contained in the crude disulfide gas fed into column 40 from coil 37. The carbon disulfide leaving the top of column 40 is free of sulphur and passes from such column into the top of a condenser 30. The carbon disulfide is caused to condense in the condenser 30 and is drawn therefrom into a cylinder 35 which receives both liquid carbon disulfide and non-condensable gases. This carbon disulfide is free of sulphur but is saturated with dissolved sulphurated gases which are removed in the column 36 by evaporation of such gases by means of the heat transferred to the column by coil 37. The pure carbon disulfide flowing from the lower section of column 36 is then cooled in a cooler 39. The non-condensable gases issuing from the cylinder 35 pass through a reflux cooler 31 and are then forced toward the plant exit by means of an extractor 32.

In order to supply the separating column 40 with the necessary liquid sulphur to effect the separation a part of the condensed carbon disulfide emanating from the column 30 and cylinder 35 is transferred by means of conduit 29 to the column 40 through a regulator valve 29' which is controlled by the temperature at a selected point 40' in the separating column 40. The substantially pure sulphur obtained at the bottom of separating column 40 is returned to the heater 21 by means of a conduit 46.

The vapors removed from the carbon disulfide in column 36 are introduced by means of a conduit 45 into the upper end of column 30 along with the vapors received from column 40.

The coal ashes are extracted by means of a gas-tight cleaning device 42 provided at the bottom of the reaction retort 13.

For starting the plant the reaction retort 13 is filled with coal which is then ignited at some suitable points. Through the different nozzles 14 air is blown in order to heat the coal to reaction temperature.

The reaction retort or oven 13 may be simply insulated with a convenient heat-insulating material. In this case the losses of heat should be low so that the temperature of the mass is held at a level sufficient to obtain a satisfactory reaction between the sulphur with the coal.

Any losses of heat may be compensated by providing an external source of heat.

On the other hand, the reaction retort 13 may be placed inside the superheating section 18 where the pre-treatment of the sulphur component is effected.

The sulphur vapor might also be directed to the bottom from the top portion thereof.

Various changes may be made in the process as well as in the means as described by way of example in the above specification without departing from the spirit of the invention or sacrificing the advantages thereof.

I claim:

1. Apparatus for producing carbon disulfide,

comprising in combination, a vertically extending heat-insulated reaction retort, a vertically extending heat-insulated preheating chamber positioned above said retort and having its lower portion in communication with the upper portion of said retort, means for feeding carbonaceous material into the upper portion of said preheating chamber, a burner for injecting a combustible gas and air into an intermediate portion of said chamber for combustion therein for heating said carbonaceous material whereby heated carbonaceous material is delivered into said retort, a gas pump for withdrawing combustible gas from the upper portion of said preheating chamber and a conduit for returning a portion thereof to said burner, a sulfur vaporizing and superheating furnace, a conduit for supplying another portion of said combustible gas to said furnace, a burner for burning said other portion of said combustible gas in said furnace to produce heat for vaporizing sulfur and superheating the resulting vapor, a conduit for supplying the resulting superheated sulfur vapor to the upper portion of said retort, and a conduit for withdrawing crude carbon disulfide vapors from the lower portion of said retort.

2. Apparatus for producing carbon disulfide, comprising in combination, a vertically extending heat-insulated reaction retort, a vertically extending heat-insulated preheating chamber positioned above said retort and having its lower portion in constantly open communication with the upper portion of said retort, feeding means for feeding carbonaceous material into the upper portion of said preheating chamber, said feeding means including a sealing device for restricting entrance of air into said preheating chamber through said feeding means, a burner positioned intermediate the upper and lower portions of said preheating chamber for introducing a mixture of air and combustible gas into said preheating chamber for combustion therein, whereby heated carbonaceous material is delivered into said retort, a gas pump for withdrawing gases due to said combustion from the upper portion of said preheating chamber to prevent entrance of said gases into said retort, sulfur vaporizing apparatus including a burner, a conduit for delivering a portion of the gases from said gas pump to said burner, a conduit for delivering sulfur gases from said vaporizing apparatus into the upper portion of said retort, and a conduit for withdrawing crude carbon disulfide vapors from the lower portion of said retort.

ERNEST CHARLES.
